SUPERVISED ELECTRICAL ALARM

Heber L. Newell, Malvern, N. Y., assignor to General Electric Company, a corporation of New York

Application October 23, 1948, Serial No. 56,084

5 Claims. (Cl. 177—311)

1

My invention relates to alarms and more particularly to solenoid-operated alarms.

It is an object of my invention to provide an improved alarm for indicating abnormal conditions.

It is another object of my invention to provide an improved alarm for indicating undesirably high temperatures.

It is a further object of my invention to provide an alarm including an improved arrangement for indicating when the alarm is not in proper condition for operation.

It is still another object of my invention to provide an improved alarm adapted to be plugged into an ordinary household electrical outlet.

Further objects and advantages of my invention will become apparent as the following description proceeds and the features of novelty which characterize my invention will be pointed out with particularity in the claims annexed to and forming part of this specification.

For a better understanding of my invention, reference may be had to the accompanying drawings in which Fig. 1 is a front elevation view, partly in section, of an alarm embodying my invention; Fig. 2 is a side elevation view, partly in section, of the alarm shown in Fig. 1; Fig. 3 is a side elevation view of a modified form of my invention; Fig. 4 is a front elevation view, partly in section, of a portion of the form shown in Fig. 3; Fig. 5 is a side elevation view, partly in section, of another modified form of my invention; Fig. 6 is a sectional view taken along the line 6—6 of Fig. 5; and Fig. 7 is a perspective view of a portion of an alarm showing still another modified form of my invention.

One application of my alarm is for indicating undesirably high temperatures in a cabinet used for storing frozen food, so that prompt action may be taken to prevent spoilage of the food. The alarm will be described in connection with such a use.

Referring now to Figs. 1 and 2, there is shown an alarm including a base 1 formed of suitable electrical insulating material. A supporting bracket 2 is secured to the base 1 by rivets 3 or other suitable fastening devices. A pair of solenoids 4 and 5 are mounted on the supporting bracket 2 with their axes in aligned relationship. The solenoid 4 is secured to the bracket 2 by a screw 6 or other suitable fastening device and the solenoid 5 is similarly secured to the bracket by a screw 7.

The solenoid 4 includes a core 8 of easily magnetizable material, such as iron, surrounded by

2

a coil 9 composed of a suitable number of turns of insulated wire. The solenoid 5 similarly includes a core 10 surrounded by a coil 11. A vibratory element or reed 12 extends transversely of the axis of the solenoids 4, 5 and is disposed midway of the gap between the opposed faces of the cores 8 and 10 of these solenoids. This reed is adapted to be vibrated by either of the solenoids 4 or 5 when energy is supplied to such solenoid from an alternating current power source. The reed 12 is mounted on a support 13 which is secured, by welding or other suitable method, to the supporting bracket 2. The supporting bracket 2 and the support 13 contain aligned openings 14, which are threaded to receive a screw 15. A cover 16 for the alarm structure is held in place by the screw 15 which passes through an opening in the cover and engages the threaded openings 14. The cover is spaced from the solenoids by spacers 17, 18.

The alarm structure is constructed so as to be received within an ordinary two-receptacle household electrical outlet 19. Power is supplied to the outlet 19 from an alternating current power source through a conventional electrical circuit including a fuse (not shown). In order to facilitate such mounting, a plurality of prongs or terminals 20, 21 are secured to the base 1 by rivets 22, 23 or other suitable fastening devices. The prongs 20, 21 are spaced so as to fit within corresponding receptacles of the two-receptacle outlet. The prongs 20 are dummy prongs for assisting in maintaining the alarm in engagement with the outlet, and are not intended to transmit power to the alarm. The prongs 21 are arranged to supply power from the electrical outlet to the solenoid 5. The prongs 21 are connected by leads 24, 25 to terminals 26 and 27, respectively, mounted on the base 1. From the terminals, current is transmitted to the solenoid 5 through leads 28, 29. In order that the outlet may still be available for other electrical devices, even though the face is covered by the alarm, a utility receptacle 30 is secured to the bottom portion of the cover 16. Power is supplied to the receptacle 30 from the terminals 26, 27 by leads 31, 32, respectively. The receptacle 30 can then be utilized to supply power through a conventional plug 33 to any electrical device.

Power for the solenoid 4 is supplied from the alternating current source of supply through a second electrical circuit including lines 34, 35. This second circuit, like the circuit for supplying the outlet 19, includes a conventional fuse (not shown), separate fuses being provided for these

two circuits. The lines 34, 35 are connected to terminals 36, 37 respectively, which are mounted on the base 1 of the alarm. The solenoid 4 is connected to these terminals through leads 38, 39. Power to the solenoid 4 is controlled by a temperature-responsive device in response to the temperature within a freezer cabinet. This device includes a thermostatic bulb 40 which is adapted to be received within a freezer cabinet (not shown) so as to be affected by the temperature within the cabinet. The bulb 40 is connected by a tube 41 to a bellows 42. The bellows, upon expansion and contraction, opens and closes a switch 43 for controlling the power supply to the solenoid 4. The temperature-responsive device is arranged so that when a satisfactory low temperature is maintained within the freezer cabinet, the switch 43 is held in its closed position; when the temperature within the freezer compartment increases above a predetermined maximum, the bellows expands to open the switch and cut off the supply of power to the solenoid 4.

The operation of the alarm is as follows. Powder is normally supplied to the solenoid 4 from the alternating current source of supply through one circuit controlled by the temperature-responsive device of the freezer. Power is supplied to the solenoid 5 from the alternating current source through a second circuit including the receptacle 19. These two circuits are separately fused so that the blowing of a single fuse will not cut out both of the circuits. The forces exerted on the reed by the solenoids 4 and 5 are substantially equal and, under normal operation, the reed 12 is maintained stationary because of the equal opposing forces exerted on the reed by these solenoids. While, for convenience, a step-down transformer may be included in the circuit of the solenoid 4 so as to reduce the voltage across the contacts of the switch 43, the relative number of turns of wire of the solenoids 4 and 5 are chosen so that the magnetomotive forces exerted by the two solenoids are equal. Should the temperature within the freezer cabinet rise above the predetermined maximum, the power supplied to the solenoid 4 is interrupted by the opening of the switch 43. The reed 12 is then acted on only by the unopposed magnetomotive force exerted by the solenoid 5 and the reed is caused to vibrate, giving off a buzzing sound to indicate to the householder unsatisfactory operation of the freezer. If desired, two projections 44, 45 may be secured to the inside of the cover 16 in a position to be engaged by the vibrating reed 12 so as to amplify the sound of the alarm.

It is possible that for some reason the fuse in the circuit supplying power to the solenoid 5 might blow thereby deenergizing this solenoid and hence causing failure of the alarm to sound when the solenoid 4 is deenergized by excessively high temperature within the freezer cabinet. However, by my arrangement, such failure of the circuit of the solenoid 5 is prevented from going unnoticed. Thus, should the supply circuit to the solenoid 5 become broken for any reason, the reed 12 is subjected to the unopposed magnetomotive force exerted by the solenoid 4, and the reed is caused to vibrate, sounding an alarm in the same manner as described above in connection with excessively high temperatures of the freezer cabinet. Hence, if upon the sounding of the alarm, the householder finds that the temperature of the cabinet is satisfactory, he can

immediately correct the defect in the power supply of the solenoid 5, insuring satisfactory operation of the alarm at all times.

My alarm structure has an additional advantage in that it does not sound should both the solenoids 4 and 5 be deenergized. It often happens that the entire power supply of an area is cut out for a short period. Since the freezer can hold satisfactory low temperatures for a period of about 24 hours, it is undesirable, should such general power failure occur during the middle of the night, for the householder to be disturbed by the sound of an alarm. If the situation has not been corrected by morning, the general power failure will be immediately apparent by the stopping of electric clocks and the failure of lights or other electrical devices to operate. Thus, the alarm is assured of operation under all conditions where such operation is necessary, but the sounding of the alarm is prevented where such operation would be of only nuisance value.

In Figs. 3 and 4 there is shown a modified form of my invention which is suitable for mounting on a flat wall in lieu of the convenience outlet mounting arrangement illustrated in Figs. 1 and 2. The structure illustrated in Figs. 3 and 4 is the same as that illustrated in Figs. 1 and 2 with the exception of the mounting arrangement, and the same numerals have been used to indicate corresponding parts in all of these figures. As shown most clearly in Fig. 3, the alarm is secured to a wall or other flat surface 46 by screws 47, 48 or other suitable fastening devices, which pass through openings in the base 1 of the alarm and into threaded engagement with the wall 46. The prongs 20, 21 are omitted from the modified form shown in Figs. 3 and 4. This form may be specifically constructed with the prongs omitted. Alternatively, however, the prongs on the form illustrated in Figs. 1 and 2 may be broken off adjacent the top of the outer surface of the base 1 by bending the prongs back and forth with a tool, such as pliers.

In order to supply power to the solenoid 5 in this modified form, leads 49 and 50 are provided from the alternating current source of supply and are connected to terminal blocks 26 and 27 respectively of the alarm. The leads 49, 50 pass through openings in the cover 16 and grommets 51, 52 of rubber or other electrical insulating material are provided between the leads and the cover.

In Figs. 5 and 6, there is illustrated another modified form of my invention in which the alarm is shaped to extend within an electrical outlet box and is provided with a single pair of prongs for reception within a receptacle associated with the outlet box. The structure illustrated includes an outlet box 53 mounted within a wall 54. An outlet structure including a flanged metal element 55 and an insulating portion 56 is secured to the outlet box by screws 57, 58. The insulating portion 56 includes two electrical receptacles 59 and 60. The receptacle 60 corresponds to the receptacle 30 in the forms previously described and is utilized to provide power for any electrical devices. The alarm structure includes an outer wall 61 formed of suitable electrical insulating material. The wall 61 includes a portion 62 which is adapted to fit snugly within a chamber 63 formed within the outlet structure. The alarm includes a pair of solenoids 4' and 5' which are positioned by screws 63' passing through openings in the wall 61. A vibratory

element or reed 12' is arranged between the solenoids and the end of the reed is adapted to strike against a projection 44'. In this form a bell 64 is used to impart a ringing sound to the alarm, and the projection 44' is secured to the inner surface of the bell 64. The bell 64 is supported on the screws 63' by a bracket 64', the bell being secured to the bracket by a bolt and nut 65. Power is supplied to the solenoid 5' from the receptacle 59 through two prongs or terminals 65', only one of which is shown in Fig. 5. Two leads 28, 29 are connected between the prongs 65' and the solenoid 5'. Power is supplied to the solenoid 4' through leads 34, 35 in the same manner as in the previously-described forms of this invention. The operation of the alarm shown in Figs. 5 and 6 is the same as that described in detail in connection with Figs. 1 and 2.

Another form of my invention is shown in Fig. 7. Only the details of the sounding mechanism are shown in this figure, but it will be apparent that these elements may be combined in an overall structure similar to that illustrated in any of the preceding figures. Referring now to Fig. 7, the alarm illustrated includes a base structure 66. Two supporting elements 67, 68 are secured to opposite ends of the base 66. A solenoid 69 is mounted on the supporting element 67. This solenoid is illustrated schematically and includes a core 70 of suitable magnetizable material and a winding 71. A similar solenoid 72 is mounted on a supporting element 68. This solenoid includes a magnetizable core 73 and a winding 74. An upright portion 75 of a supporting element 68 is provided with a slot 76, and a vibratory element or armature 77 is pivotally mounted within the slot 76. A corresponding vibratory element or armature 78 is mounted within a slot 79 in an upright portion 75' of the supporting element 67. The armatures 77 and 78 include extended portions 80, 81 respectively which are bent slightly upwardly from the plane of the remainder of each of the armatures. These extended portions 80, 81 are connected by a spring 82 which holds the armatures in position against the upright portions 75 and 75' and also biases each of the armatures away from its corresponding solenoid. The two armatures 77, 78 are interlocked by overlapping arms 83, 84, and 85, 86 so as to prevent vibration of either when both solenoids 69 and 72 are energized. A depending striker 87 is secured to the arm 83 and a corresponding striker 88 is secured to the arm 85. Each of these strikers is adapted upon vibration of the armature with which it is associated, to strike a sounding plate 89 to give an alarm indication.

As in the forms previously described, one of the solenoids, for example, solenoid 69, is supplied from an alternating current source through a first circuit including a switch controlled by a temperature-responsive device associated with a freezer cabinet and the other solenoid, for example, solenoid 72, is supplied from the alternating current source through a second, separately-fused circuit. When both solenoids are energized the armatures or vibratory elements 77, 78 mutually prevent vibration because of the overlapping arms 83, 84 and 85, 86. Thus, when the armature 77 is pulled into engagement with the core 73 because of energization of the solenoid 72, the arm 84 is forced upwardly into engagement with the arm 83 of the armature 78, and vibration of the armature 78 is prevented. Similarly, when solenoid 69 is energized the arm

86 engages the underside of the arm 85 and prevents vibration of the armature 77.

Should the solenoid 69 become deenergized because of the breaking of the first circuit by the temperature-responsive device as a result of an excessively high temperature in the freezer cabinet, the armature 78 is pulled away from the solenoid 69 by the spring 82, because of the upwardly extending construction of the portion 81 of the armature. The arm 86 is thereby moved downwardly out of engagement with the arm 85 of the armature 77. The armature 77 is enabled to vibrate under the influence of the alternating current solenoid 72 and this vibration is translated through the striker 87 and the sounding plate 89 into an alarm sound, warning of the high temperature in the freezer cabinet. Similarly, should the fuse of the second circuit blow, deenergizing the solenoid 72, the arm 84 is moved out of engagement with the arm 83 of the armature 78, and the striker 87 is enabled to strike the sounding plate 89 to give an alarm sound. Should both solenoids become deenergized simultaneously because of a general power failure, for example, no alarm is sounded.

While the foregoing description has been directed primarily to the use of this alarm with freezers to indicate undesirably high temperatures, it will be apparent that the alarm can be used equally well to indicate other abnormal conditions. For example, the switch 42 in Fig. 1 could be operated by a pressure-responsive device so that the alarm would indicate abnormally high or abnormally low pressures, or the switch could be operated by a speed-responsive device, in which case the alarm would indicate abnormally high or abnormally low speeds. I intend, by the appended claims, to cover all modifications within the spirit and scope of my invention.

What I claim as new and desire to secure by Letters Patent of the United States is:

1. An alarm comprising a first solenoid adapted to be energized from a first electrical circuit, a second solenoid adapted to be energized from a second electrical circuit, said first circuit and said second circuit being separately fused, a vibratory element positioned for actuation by said first solenoid, said second solenoid exerting a force on said vibratory element opposing such actuation, said first and second solenoids exerting substantially equal forces on said element whereby said element remains stationary when both of said solenoids are energized, and condition-responsive means for deenergizing said second solenoid to permit actuation of said element by said first solenoid.

2. An alarm comprising a first solenoid adapted to be energized from a first electrical circuit, a second solenoid adapted to be energized from a second electrical circuit, said first circuit and said second circuit being separately fused, a vibratory element positioned for actuation by either of said solenoids to sound an alarm, each of said solenoids preventing actuation of said element by the other of said solenoids when both of said solenoids are energized, and condition-responsive means for deenergizing said second solenoid to permit actuation of said element by said first solenoid.

3. An alarm comprising a first solenoid adapted to be energized from a first electrical circuit, a second solenoid adapted to be energized from a second electrical circuit, said first circuit and said second circuit being separately fused, a supporting structure for said solenoids, said solenoids

being mounted on said structure with their axes in alignment, a vibratory element positioned between said solenoids and extending transversely of said aligned axes, said solenoids exerting substantially equal and opposite forces on said element whereby said element is maintained stationary, and condition-responsive means for de-energizing said first solenoid whereby vibration of said element is induced by said second solenoid.

4. An alarm comprising a first solenoid adapted to be energized from a first electrical circuit, a second solenoid adapted to be energized from a second electrical circuit, said first circuit and said second circuit being separately fused, a first vibratory element pivotally mounted adjacent said first solenoid for actuation thereby, a second vibratory element pivotally mounted adjacent said second solenoid for actuation thereby, each of said elements including a portion adapted to engage the other of said elements for maintaining said elements stationary when both of said solenoids are energized, and condition-responsive means for deenergizing said first solenoid whereby said first element is released to permit actuation of said second element by said second solenoid.

5. An alarm comprising a housing, a pair of

5

10

15

20

25

solenoids mounted within said housing, a vibratory element positioned between said solenoids, said solenoids when energized subjecting said element to substantially equal opposed forces whereby said element is maintained stationary, a pair of prongs adapted to be received within a household electrical outlet, said prongs being connected to one of said solenoids for supplying power from a first electrical circuit to energize said one of said solenoids, a second electrical circuit for supplying power to energize the other of said solenoids, said first circuit and said second circuit being separately fused, and condition-responsive means for deenergizing said other of said solenoids to permit actuation of said element by said one of said solenoids.
